UNITED STATES PATENT OFFICE.

HOWARD H. MEAD, OF QUINCY, MICHIGAN.

STEAM-TRAP.

1,376,214.

Specification of Letters Patent. Patented Apr. 26, 1921.

Application filed September 24, 1919. Serial No. 325,967.

To all whom it may concern:

Be it known that I, HOWARD H. MEAD, a citizen of the United States, residing at Quincy, in the county of Branch and State 5 of Michigan, have invented certain new and useful Improvements in Steam-Traps, of which the following is a specification.

This invention relates to steam traps, and has for one of its objects to simplify and 10 improve the construction and increase the efficiency and utility of the same.

Another object of the invention is to provide a device of this character of few parts, readily and quickly assembled and in 15 which repairs and adjustments may be easily made.

Another object of the invention is to provide a device of this character in which the action may be observed without shutting 20 off the flow of the steam.

With these and other objects in view, the invention consists in certain novel features of construction as hereafter shown and described and then specifically pointed out in 25 the claims, and in the drawings illustrative of the preferred embodiment of the invention.

Figure 1 is a longitudinal sectional elevation.

Fig. 2 is a plan view with the shell in 30 section on the line 2—2 of Fig. 1.

Fig. 3 is a view similar to Fig. 1 illustrating a modification in the construction.

Figs. 4 and 5 are sectional details illustrating the improved trap arranged as a 35 balanced valve.

Like reference characters indicate corresponding parts in all the figures.

The improved trap comprises a main 40 body or shell formed of a relatively large, preferably cylindrical, portion 10 and a reduced, preferably oblong, communicating portion 11.

The side walls of the reduced portion 11 45 of the shell are connected by a horizontal partition 12 and a vertical partition 13 forming an air or expansion chamber 14 therein as shown.

The side walls of the portion 11 of the 50 shell are likewise connected by a web 15 having an internally threaded "boss" 16 to receive the intake pipe 17.

The lower sides of the portions 10 and 11 55 of the shell are closed by a continuous bottom 18, the part of the bottom which is disposed beneath the portion 11 being de-

pressed as shown to form a settling chamber.

The cylindrical portion 11 of the shell is provided with a detachable closure 19 60 preferably arched upwardly as shown, while the chamber 14 is provided with a detachable closure 20. By this arrangement the two parts of the interior of the shell are readily and independently accessible. 65

Formed through the bottom 12 of the chamber 14 is an opening 21 having a valve seat to receive a downwardly opening valve 22.

A relatively large float 23 is located 70 within the portion 10 of the shell, and is provided with a depending hanger 24 to which an operating lever 25 is pivoted as shown at 26.

The lever is provided with a plurality of 75 apertures for the pivot 26 so that the lever may be adjustably coupled to the hanger and float. The float is thus free to adapt itself to the level of the water in the casing 10 and engages the same with equal pressure at all points. 80

Supports 28 are formed upon the inner faces of the side walls of the reduced portion 11 and recessed, preferably in V shape, to receive the terminals of the fulcrum pins 85 of the lever 25, as shown.

The fulcrum element of the lever 25 is located relatively near the valve 22, to provide a strong leverage to the float in its 90 operation of the valve.

By this arrangement, it will be obvious that the vertical movement of the float will control the position of the valve 22.

The bottom 12 of the chamber 14 is spaced 95 a considerable distance above the bottom of the shell, and the water will stand normally above the lower line of the chamber, or so that the lower portion of the chamber is constantly immersed in the water. The only means of communication between the body 100 of the shell and the chamber 14 is through the valve opening 21, and this opening is "sealed" by the condensate in the shell in coaction with the valve 22.

By this arrangement the steam under pressure 105 will not pass to the chamber 14, while the surplus condensate when a sufficient amount accumulates to elevate the float 23 above a predetermined distance, will open the valve 22 and permit the surplus to pass 110 to the chamber 14 and thence through the escape pipe 29.

The water flowing into the chamber 14 expands and the pressure is thereby equalized so that it flows uniformly through the discharge 29, and all danger of pounding or unequal pressure obviated. The chamber 14 thus serves as an expansion or "air chamber" and is an important feature of the device.

Another important function of the chamber 14 is that the valve 22 or its seat are 10 unaffected by any bending or displacing of the discharge pipe 29, when assembling or installing the apparatus.

By providing the stem 27 of the valve 22 with the adjusting nuts, as shown, the valve 15 may be set to open at any predetermined stage of the condensate. With a trap thus constructed it is immaterial how high or low the pressure may be as it will not permit steam to pass to the chamber 14, nor will it 20 hold water back, and cause it to overflow into the coils or other portions of the system.

The capacity of the shell will be gaged by the sizes of the pipes and coils associated 25 with the trap.

When the trap is installed in a line under boiler pressure, with a discharge pipe 29 about 1 inch in diameter, the capacity of the trap will be equal to the amount of condensate 30 that can be forced through a 1 inch pipe at the pressure under which the trap is working no matter what the gage pressure may be.

The improved trap may also be effectually 35 used in an exhaust steam line, as will be obvious.

The trap operates automatically after being properly installed and adjusted and automatically regulates itself and does not depend 40 upon the expansion or contraction of members.

If found necessary the cover 20 of the chamber 14 may be detached without disconnecting the trap, as the steam cannot 45 blow through, thus permitting the inspection of the interior of the chamber and the operativeness of the valve 22 at all times.

Detachable plugs indicated at 30 are preferably provided in the walls of the shell 50 opposite the fulcrum device to enable the latter to be inspected without removing the bottom 18 or other parts.

The whole shell or body is in four parts only, connected by bolts or like fastening de-

vices, and also provided with suitable dowel 55 pins, indicated at 31, to insure the ready and accurate assembling of the parts, and the corresponding accurate seating of the valves.

Under some circumstances a more rapid discharge of the condensate may be required, 60 and in that case the modification shown in Fig. 3 may be employed consisting in providing an opening 32 in the deflected portion of the bottom 18 and seating a valve 33 in its inner end and coupling this valve 65 by its stem 34 to the lever 25. When the modified structure is employed the opening 21 will be moved nearly to the discharge end of the chamber 14 and the fulcrum device located midway between the valves. 70

By this arrangement the valves will be operated simultaneously and the discharge of the condensate accelerated.

The intake 17 may be located at other points than in the web 15, if required, for 75 instance in the main body 10 as indicated by dotted lines 35 in Fig. 1.

The improved device may likewise be arranged for use as a "balanced" valve, as 80 shown in Figs. 4 and 5.

What I claim is:

1. In a trap of the class described, a casting including a laterally enlarged chamber at one end and an elevated expansion chamber at the other end, said elevated chamber having an intake valve and a discharge opening, a lever poised near one end and attached at its shorter end to the valve, and a float within the enlarged chamber and pivotally supported on the longer end of the 85 lever.

2. In a trap of the class described, a casting including a laterally enlarged chamber at one end and an elevated chamber at the other end and a settling chamber beneath 95 the elevated chamber, said elevated chamber having an intake valve and a discharge opening and said settling chamber having a depression in alignment with the valve, a piston operative in the depression and connected 100 to the stem of the valve, a lever poised near one end and attached at its shorter end to the stem of the valve, and a float within the enlarged chamber and supported by the longer end of the lever. 105

In testimony whereof, I affix my signature hereto.

HOWARD H. MEAD.
